Filed Jan. 5, 1960, Ser. No. 58,932

Term of patent 7 years

(Cl. D15—1)

FIG. 1

Figures 2, 3 and 4 are top, front and side views respectively, of the portion of the chair shown in solid lines in Figure 1; and

The dominant feature of my design resides in that portion shown in full lines in Figure 1 and shown in detail in Figures 2, 3, 4 and 5.

I claim:

The ornamental design for a chair, substantially as shown and described.
